UNITED STATES PATENT OFFICE.

FRANK E. CASE, OF SCHENECTADY, NEW YORK, ASSIGNOR TO GENERAL ELECTRIC COMPANY, A CORPORATION OF NEW YORK.

CURRENT-COLLECTOR.

1,098,661.

Specification of Letters Patent.

Patented June 2, 1914.

Application filed August 1, 1906. Serial No. 328,685.

To all whom it may concern:

Be it known that I, FRANK E. CASE, a citizen of the United States, residing at Schenectady, county of Schenectady, State 5 of New York, have invented certain new and useful Improvements in Current-Collectors, of which the following is a specification.

The present invention relates to electric 10 railways and more especially to the apparatus carried by the vehicle for collecting electric current from a stationary conductor supported parallel to the roadway.

It is sometimes impracticable or impossi- 15 ble to employ a single type of stationary conductor, that is either a third rail or an overhead conductor, throughout a system of trackage over which the vehicle is to run. Accordingly it is the practice in such in- 20 stances to provide one section of the roadway with one type of stationary conductor and another section with another type of conductor and furnish the vehicle with two or more collecting devices adapted to co- 25 operate with the respective types of conductors.

When one of the collecting devices runs off the end of its conductor or its function is no longer desired, it is necessary that it 30 be withdrawn from its operative position so that it may not come in contact with stationary projections or objects positioned along the roadway.

The objects of my invention are to pro- 35 vide an improved current collector, which will automatically assume retracted position in case any part breaks or fails to function properly, and to provide automatic means for both retracting and restoring the col- 40 lector to operative position.

In the accompanying drawing which forms a part of this specification, I have shown two overhead current collectors and a diagrammatic arrangement of pipes and 45 controlling valves, embodying one form of my invention.

On electric locomotives and cars where the consumption of current is relatively large it is customary to provide a collector 1 at each 50 end of the vehicle and also two collector con-

trolling valves 2, either of which is adopted to control both collectors simultaneously.

Each current collector comprises a sliding contact shoe 3 adapted to engage the under- 55 side of an overhead conductor and is carried at the upper ends of two toggle-levers 4, 5 which are fulcrumed upon a pedestal 6. The upper members 4 of the toggles extend beyond their pivotal connections with the lower members 5, and engage tension 60 springs 7 which are connected at their inner ends to collapsible arms 8 which normally stand in the positions indicated in the drawing so that springs 7 are put under tension to exert a pull upon the toggles in such manner as to urge the contact shoe 3 upwardly. The lower members 5 are provided at their inner ends with intermeshing gears 5' whereby they are caused to move up and down in unison, and below their fulcrums 70 the levers are expanded into shells or hoods for the purpose of protecting the pilot valves and levers located therebeneath. In order to provide good electrical connection between the collector shoe 3 and the pedestal 6 without interfering with the free movement of the toggle levers, the former are connected by flexible conductors 9. The collapsible arms 8 are fixed to short shafts 10 journaled in the bifurcated upper end of the pedestal 6 80 and to the center of the shafts are fixed short arms 11 which are connected by links 12 to a cross-head 13 carried at the upper end of a piston rod 14. The piston rod is provided with a shoulder 15 which in ele- 85 vated position engages a shoulder on the inside of the pedestal, so that it is arrested in proper position to sustain the arms 8 as shown with the springs 7 crossing somewhat below the dead centers thereof. The lower 90 end of the rod 14 carries a piston 16 which is movable up and down in a cylinder 18 at the lower end of the pedestal and a light spring 17 surrounds the rod 14 and thrusts against the top of the piston 16 and the 95 shoulder on the inside of the pedestal so as to coöperate with the weight of the rod and piston and the parts carried thereby to move them downward positively despite any opposing friction whenever the air pressure is 100

relieved from the lower side of the piston 16. The spring 17 may be omitted if desired since the only function performed thereby is to assure the downward movement of the 5 piston when released from the upward pressure of the compressed air.

The lower end of the cylinder 18 is closed by a screw plug having delivery port therein through which compressed air is supplied 10 to the cylinder by a pipe 19 connecting with a delivery port 20 of the collector controlling valve 2. The controlling valve is connected by a pipe 21 with a suitable source of compressed air and has an exhaust port 22 normally closed by a slide valve 23 but adapted to be moved so as to connect the delivery port 20 with the exhaust port 22. The means for moving the slide valve 23 consists of a doubled ended piston 24 between 15 the ends of which the slide valve is positioned and it is purposely left unpacked so that the compressed air supplied through pipe 21 may escape thereabout and establish balanced pressures on both ends thereof. 20 The piston 24 is caused to move to the right or left by permitting the air at the right or left end thereof to escape therefrom so as to effect an unbalancing of pressures at the opposite ends. The escape of air from 25 the ends of the piston 24 is manually controlled by a hand lever 25 pivoted upon the main valve and having two arms which overlie tappet valves 26 at the respective ends of the collector operating valve 2. The 30 escape of air from the ends of the piston 24 is also automatically controlled by two pilot valves 27 and 28 located on opposite sides of the collector pedestal 6 and inversely connected to the opposite ends of the collector operating valve 2 by vent pipes 29 and 30. The pilot valves are alike and each 35 comprises a simple valve box 31 bolted to the pedestal with a spring pressed valve 32 normally closing a vent port 33. The valves 40 27 and 28 are provided with spring-pressed levers 34 and 35 which engage at their lower ends with the outer ends of the stems of the valves 32.

The upper ends of the levers are provided 45 with cam surfaces 34' and 35' which coöperate with projections 36, 37 carried by the lower arms 5 of the toggles. The cam surface 34' and the projection 36 are so disposed that they will engage and trip pilot 50 valve 27 whenever the collector shoe 3 moves above a predetermined level as by passing off the end of a conductor section, thereby allowing the air in the right hand end of the collector operating valve 2 to escape, causing 55 the piston 24 and the slide valve 23 to move to the right, connecting the delivery port 20 with the exhaust port 22 and thereby permitting the air pressure in the collector 60

cylinder 18 to exhaust and the collector to drop. The cam surface 35' and the projection 37 are so disposed that they will engage and trip pilot valve 28 whenever the collector shoe 3 is forced below its normal withdrawn position, as by a projection arranged on the stationary conductor at the 70 point at which it is desired to restore the collector to working position. The tripping of pilot valve 28 allows the air in the left hand end of the collector operating valve to escape through pipe 30, causing the piston 24 and 75 the slide valve 23 to move to the left closing the exhaust port 22 and opening the delivery port 20 so that compressed air passes through pipe 19 to the cylinder 18 of the current collector and raises the shoe 3 into 80 its normal running position.

The air pipes 19, 29 and 30 connect with both current collectors 1 and with both collector operating valves 2 so that both collectors are simultaneously actuated by either 85 collector operating valve, and in order to prevent the air exhausting from one valve through the other, a double check valve 38 is arranged in pipe 19.

I do not desire to restrict myself to the 90 particular form or arrangement of parts herein shown and described since it is evident that they may be changed and modified without departing from my invention as defined in the appended claims.

What I claim as new, and desire to secure by Letters Patent of the United States, is,—

1. The combination with a current collector for electric vehicles, of pneumatically actuated power means for raising and lowering said collector, and automatic means actuated by the movements of said collector for controlling the admission of the pressure fluid to the power means and the exhaustion therefrom.

2. The combination with a current collector for electric vehicles, of pneumatically actuated power means for raising and lowering said collector, a controlling valve for regulating the supply and exhaustion of the 110 pressure fluid, and two pilot valves actuated by the movements of the collector, for governing said controller valve.

3. The combination with a current collector for electric vehicles, of pneumatically 115 operated power means for raising and lowering said collector, a controlling valve for regulating the supply and exhaustion of the pressure fluid, a pilot valve actuated by the movement of the collector in one direction 120 to move the controlling valve into exhaust position, and a second pilot valve actuated by the movement of the collector in the other direction to move the controlling valve into supply position.

4. The combination with a current col-

lector for electric vehicles, of tension means for urging said collector into engagement with the stationary conductor, a crank device to which said tension means is connected, 5 and power means for rotating said crank device to tension or relieve said tension means.

In witness whereof I have hereunto set my hand this 31st day of July 1906.

FRANK E. CASE.
